(57) **CLAIM**

The ornamental design for a scar therapy patch, as shown and described.

DESCRIPTION

FIG. 1 is a front view showing an embodiment of a scar therapy patch of our design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

Broken lines illustrate portions of the patch that form no part of the claimed design.
